UNITED STATES PATENT OFFICE.

JEROME S. MOSELEY, OF SYRACUSE, NEW YORK.

ROTARY ENGINE.

SPECIFICATION forming part of Letters Patent No. 732,880, dated July 7, 1903.

Application filed March 13, 1902. Serial No. 97,971. (No model.)

To all whom it may concern:

Be it known that I, JEROME S. MOSELEY, of Syracuse, in the county of Onondaga and State of New York, have invented a certain 5 new and useful Rotary Engine, of which the following is a specification.

My invention has for its object the production of a rotary engine which is particularly simple in construction, economical in manufacture, and highly efficient and durable in use; and to this end it consists in the devices and combinations hereinafter set forth and claimed.

Figure 1 is an edge view, partly broken away, of a preferred embodiment of my invention. Fig. 2 is an elevation of the rotary engine seen in Fig. 1, a portion of the casing for the intermeshing gears being removed. Fig. 3 is a vertical sectional view taken on line 3 3, Fig. 1. Fig. 4 is a view similar to Fig. 3, one side of the casing of the engine being removed and the piston-disks being shown in their positions assumed at the commencement of the entrance of the motive fluid. Fig. 5 is an elevation of the lower portion of the parts seen in Fig. 4, the piston-disks being shown in their positions assumed when their projecting arms are about to enter the cut-outs extending inwardly from the peripheries of said piston-disks. Figs. 6 and 7 are face views of the inner sides of the sections of the casing of my engine, a portion of said casing being shown in section in Fig. 7. Fig. 8 is a sectional view taken on line 8 8, 35 Fig. 3.

My rotary engine consists, essentially, of a casing A and piston-disks B B'. The casing A is of any desirable form, size, and construction, is preferably composed of separable sections a a', united by suitable securing means a², and is provided with two substantially cylindrical parallel chambers a³ a⁴, merging together at contiguous sides, and inlet and outlet ports a⁵ a⁶, having diverging branches a⁷ a⁸, communicating with the chambers a³ a⁴ at opposite sides of their point of union. The branches a⁷ of the inlet-port a⁵ are generally connected to the chambers a³ a⁴ by arc-shaped grooves a⁹ a¹⁰, formed in opposite walls of said chambers; and, as best seen in Fig. 6, the ends of the grooves a⁹ nearest the port a⁵ are nearer to the point of union

of the chambers a³ a⁴ than the contiguous ends of the grooves a¹⁰ in order that said grooves a⁹ a¹⁰ may conduct the motive fluid to the passages, presently described, of both piston-disks B B' at substantially the same time.

The piston-disks B B' are supported, respectively, in the chambers a³ a⁴ and are arranged substantially concentric therewith, and, as best seen in Figs. 4 and 5, their peripheries roll in contact. Said piston-disks B B' are each provided with a cut-out b, extending inwardly from its periphery, an arm-abutment b', projecting from said periphery and movable in engagement with the inner face of the corresponding chamber and into the cut-out of the opposite piston-disk, and a passage b², opening through opposite sides of said piston-disk in alinement with the inlet-grooves a⁹ a¹⁰ in the opposite walls of the corresponding chamber and also opening through the rear wall of said arm b'. The cut-outs b and the arms b' are so relatively arranged that at the commencement of the entrance of the motive fluid the arm b' of the piston-disk B is nearer the point of union of the chambers a³ a⁴ than the corresponding part of the piston-disk B', and consequently said arms b' readily enter the cut-outs b without any interference with each other. The piston-disks B B' are suitably connected to driving-shafts B², provided with intermeshing pinions B³, which are arranged in a casing B⁴ and operate to cause the arms b' to always register with the cut-outs b.

In the operation of my rotary engine the motive fluid admitted through the port a⁵ passes through its diverging branches a⁷ and the grooves a⁹ a¹⁰ to opposite sides of the piston-disks B B' and thence through the passages b² to the rear of the arms b', effecting rotation of the piston-disks. As said piston-disks continue their movement the inlet-openings of the passages b² are rotated beyond the grooves a⁹ a¹⁰, whereupon the entrance of the motive fluid is cut off, and said motive fluid previously admitted within the chambers a³ a⁴ is then used expansively until the arms b' pass the diverging branches a⁸ of the port a⁶ and permit said fluid to exhaust through the port a⁶. The friction incidental to the rotation of the piston-disks is reduced to a minimum,

owing to the rolling of said disks upon each other and the admission of the motive fluid at opposite sides thereof.

The construction and operation of my rotary engine will now be readily understood upon reference to the foregoing description and the accompanying drawings, and it will be particularly noted that more or less change may be made in the component parts thereof without departing from the spirit of my invention.

Having thus fully described my invention, what I claim as new, and desire to secure by Letters Patent, is—

1. A rotary engine comprising a chamber, a revolute piston-disk supported in the chamber and arranged substantially concentric therewith, said piston-disk being provided with an arm projecting from its periphery and engaging the inner face of the chamber and with a passage leading from opposite sides of said disk through the rear face of said arm, means for conducting the motive fluid to opposite sides of said passage, substantially as and for the purpose set forth.

2. A rotary engine comprising a casing having two chambers therein, a piston concentrically mounted in each chamber, said pistons having their peripheries in contact and provided with abutments arranged one in advance of the other, steam-passages having their outlets arranged one in advance of the other, and steam-inlet passages for each chamber in said casing having their discharge-openings into the chambers arranged one in advance of the other, substantially as described.

3. In a rotary engine, the combination of a casing having two chambers, a piston mounted in each chamber having an abutment, the abutment of one piston being arranged in advance of the abutment of the other, steam-passages in each piston opening out through the sides thereof in radial alignment with its abutment, and a steam-passage in each chamber coaxing with the passage in the piston associated therewith, the passage in one of said chambers having its outlet arranged in advance of the outlet end of the passage in the other chamber, substantially as described.

4. A rotary engine comprising two substantially cylindrical parallel chambers merging together at contiguous sides, two piston-disks supported respectively in the chambers and arranged substantially concentric therewith, said piston-disks having their peripheries in contact and being each provided with a cut-out extending inwardly from its periphery, an arm projecting from said periphery and

movable into the cut-out of the opposite piston-disk, and a passage opening through opposite sides of the piston-disk and the rear face of the arm for conducting the motive fluid to the rear of said arm, and arc-shaped grooves in opposite sides of each chamber for conducting the motive fluid to the passage of the corresponding piston-disk, substantially as and for the purpose set forth.

5. A rotary engine comprising two substantially cylindrical parallel chambers merging together at contiguous sides, two piston-disks supported respectively in the chambers and arranged substantially concentric therewith, said piston-disks having their peripheries in contact and being each provided with a cut-out extending inwardly from its periphery, an arm projecting from said periphery and movable into the cut-out of the opposite piston-disk, and a passage for conducting the motive fluid to the rear of the arm, and inlet and outlet ports having diverging branches communicating with the chambers at opposite sides of their point of union, substantially as and for the purpose described.

6. In combination, a casing having companion chambers, and a piston provided with a radial abutment concentrically mounted in each chamber, said casing having a central inlet-passage provided with branches leading therefrom contained wholly within the side walls thereof, said branches terminating in passages opening out through said side walls and extending concentric to the axes of the pistons, substantially as described.

7. In combination, a casing having companion chambers, and a piston provided with a radial abutment concentrically mounted in each chamber, said casing having a central inlet-passage provided with branches leading therefrom contained wholly within the side walls thereof, said branches terminating in passages opening out through said side walls and extending concentric to the axes of the pistons, one of said branches opening out in one of said piston-chambers a less distance from said central inlet than the other branch, substantially as described.

In testimony whereof I have hereunto signed my name, in the presence of two attesting witnesses, at Syracuse, in the county of Onondaga, in the State of New York, this 1st day of October, 1901.

JEROME S. MOSELEY.
